(57) **CLAIM**

The ornamental design for a cartridge drive, as shown and described.

DESCRIPTION

FIG. 1 is a front perspective view of a cartridge drive showing my new design;

FIG. 2 is a top perspective thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line showing in FIG. 8 represents the bounds of the claimed design while all other broken lines are directed to unclaimed portions of the cartridge drive; the broken lines form no part of the claimed design.

1 Claim, 6 Drawing Sheets
